UNITED STATES PATENT OFFICE.

HENRI EDMOND CASGRAIN, OF QUEBEC, CANADA.

CARBURETER FOR EXPLOSIVE-ENGINES.

SPECIFICATION forming part of Letters Patent No. 633,800, dated September 26, 1899.

Application filed October 18, 1898. Serial No. 693,941. (No model.)

To all whom it may concern:

Be it known that I, HENRI EDMOND CASGRAIN, dentist, a subject of Her Majesty the Queen of Great Britain, residing at 51 St. John street, Quebec, Province of Quebec, Canada, have invented certain new and useful Improvements in Carbureters; and I do hereby declare the following to be a full, clear, and exact description of the invention, such as will enable others skilled in the art to which it appertains to make and use the same.

This invention relates to carbureters, particularly those for internal-combustion engines, and I will describe it as adapted to an engine of that description operated by petroleum-spirit, though I wish it to be understood that its application is not restricted to spirit only, as I may use this invention with even heavy hydrocarbon oils.

One of the objects of the invention is to effect the admixture of the air and fuel and the vaporization of the spirit by "pulverization" rather than by heat, though I may employ heat if I so desire.

The details and general form of the apparatus employed in carrying out this invention may vary; but one way in which it may be practiced will now be described, with reference to the accompanying drawings, in which—

Figure 1 is a vertical central section through a complete carbureter. Fig. 2 is a plan of the carbureter, half in section, on the line 2 2 of Fig. 1. Fig. 3 is an under side view of the carbureter, half in section, on the line 3 3 of Fig. 1. Fig. 4 is a sectional plan on the line 4 4 of Fig. 1, and Fig. 5 is a plan of a fan mixing-wheel, at its circumference, employed in the carbureter to "pulverize" or finely divide the oil and to control the oil-valve in the manner hereinafter described.

Like letters indicate like parts throughout the drawings.

A is a cylindrical vessel communicating by a branch A' with the engine-cylinder, combustion-chamber, or admission-valve chamber. At the lower portion of this vessel is a disk B, into which oil or other liquid fuel is delivered by gravitation or by a pump or otherwise from the passage B', which extends into the disk, as shown. From this disk a central pillar B² extends upward into the vessel A.

A minute passage-way B³, "flared" at its upper end, affords communication between the passage B' and the interior of the lower end of the pillar, whence small passages B⁴ extend laterally through the sides of the pillar and open into the space around it. A screw-plug B⁶ enables access to be had, when desired, to the passage-way B³. Within the pillar B² is a spindle C, adapted to rotate freely therein and carrying at its upper end a fan mixing-wheel C', which has blades C³ at its circumference, said wheel almost filling the bore of the vessel A, so that none of the explosive mixture passing through the apparatus can escape the action of the fan mixing-wheel. The lower end C² of the spindle is tapered to constitute a valve which seats itself in the passage-way B³. The construction and mode of operation of this device C C' C³ are important features of the present invention, as will hereinafter appear. Around the base of the pillar B² are air-conduits D, extending through the disk B from the bottom to the top. A non-return valve E, with three wings E, encircles the pillar B² immediately below the passages B⁴ and rests upon the top face of the disks, with its wings over the upper ends of the air-conduits. This valve readily rises to permit air to ascend past the pillar B² through the passage-way, which is constricted around the pillar B², in order that the speed of the air-current through the apparatus shall be a maximum in that passage-way. The valve E automatically shuts down over the air-conduits D to prevent any return of air and vapor through them. The extent of its lift is limited by a flange B⁵ on the pillar B², and an angular portion B⁷ of the pillar passes through a corresponding angular hole E² in the center of the valve and prevents the valve from rotating out of its proper position above the conduits D.

The constricted passage A⁶ is formed by the tube A⁷, which is mounted in a partition A⁸, integral with the interior of the casing or vessel A. This tube surrounds the pillar B² and is concentric therewith and terminates at its lower portion near the passage B⁴. The upper portion of the tube A⁷ extends upwardly to a point slightly below the top of the pillar B². The diameter of the passage A⁷ may be

of any suitable size, but as shown it is of considerably less diameter than that of the casing or vessel A.

Air drawn by the engine through the constricted passage A⁶ around the pillar B² will raise the fan-wheel C', the extent of its lift being adjustable by the device hereinafter described. As it rises it lifts the spindle C, which raises the valve C² and permits the petroleum-spirit or other liquid fuel to escape from the disk B by way of the passage-way B³ into the interior of the pillar B², whence it issues laterally in fine streams from the two small passages B⁴ into the air, flowing past the wings E' of the valve E upward around that pillar. The speed of the current through the apparatus is increased upon its entry into the constricted passage-way A⁶, this increase of speed producing an aspiratory action upon the gasolene or other liquid fuel, and thus tending to maintain uniformity of the flow of liquid fuel from the orifices B⁴ despite any variation which may occur in the level or pressure of oil in the passage B'. The air and liquid fuel meeting and ascending in the vessel A, as described, act upon the blade C³ of the fan mixing-wheel C' to rotate the wheel, and the blades in turn react on the air and liquid, mingling them intimately and beating up and finely subdividing the oil, the explosive mixture thus produced passing to the engine by the branch A'.

The spindle C, disk C', valve C², and blades C³ rise only for the suction-stroke of the engine under the action of the updraft through the apparatus which acts upon the wheel to lift it and upon the blades C³ to spin it in the direction indicated by the arrow in Fig. 5. As soon as the updraft ceases, the wheel, continuing to spin by reason of its own momentum, screws itself down in the air and vapor in the vessel A and not only permits the spindle C to drop and close the valve C², but also forces that valve against its seat more quickly than if gravity alone acted on it, and also more tightly, so that the valve will not reopen accidentally under the influence of vibration or of alteration of level of the liquid fuel, but will only lift again on the occurrence of the next suction stroke.

In this improved carbureter the necessary fine division of the fuel is effected without the necessity for applying heat, and although I do not bind myself to this I prefer to employ a non-conducting casing outside the previously-mentioned vessel A to prevent any unnecessary accession of heat to the vessel, which is provided with an outer casing A², within which a layer A³ of a bad conductor of heat is retained against the wall of the vessel.

As the amount of fuel supplied to the engine is controlled by the extent to which the fan-wheel spindle C is raised, and, consequently, the valve C² opened, means should be provided for varying the amount of this movement. In the example illustrated this control is effected by a screw F, passing

through the cover A⁴ of the vessel A and extending down into proximity with the upper end of the spindle C. A spring-arm F' is secured upon the outer end of the screw F, by which it may be screwed in or out, as desired. This spring-arm has a point F², adapted to engage with one or more depressions A⁵, formed in the cover A⁴, so as to retain the screw F in any position to which it may be adjusted for regulating the amount of lift of the valve-spindle C.

It is preferred to guard against return flow of vapor and air from the carbureter by means additional to the valve E, previously mentioned, and for this purpose it is preferred to employ an air-chamber G, screwed to the lower end of the vessel A, the air passing into this chamber through, first, a wire-gauze screen G', fixed across its lower end, and, second, a leather or other suitable non-return valve G², secured in the airway just within the screen and forming a safeguard against return flow additional to that afforded by the valve E.

The admission of the air through the screen or to the chamber generally may be controlled by a cap or disk H, screwed onto a stem G³, extending from the lower end of the chamber G and capable of being adjusted nearer to or farther from the screen, as desired. I have above explained that I prefer to keep this carbureter cold, my reason for this being that I find that by introducing the explosive mixture into the cylinder of the engine at a low temperature I obtain better results than if it were introduced hot. The expansion of the cold mixture in the hot cylinder increases its pressure, and the coolness of the entering charge reduces the quantity of jacket water or air required or obviates the necessity for relying on an external medium for cooling the cylinder.

What I claim is—

1. A carbureter for explosive-engines, comprising a casing, a fluid-inlet in the lower portion of said casing, an air-inlet below said fluid-inlet, a valve for the fluid-inlet controlled by the action of the engine, a valve for closing the air-inlet, and a fan mixing-wheel connected with the fluid-inlet valve and adapted to be rotated by the inflow of the combined air and fluid, substantially as described.

2. A carbureter for explosive-engines, comprising a casing, a fluid-inlet in the lower portion of said casing, an air-inlet below said fluid-inlet, a valve for the fluid-inlet controlled by the action of the engine, a valve controlling the air-inlet, a fan mixing-wheel connected with the fluid-inlet valve and adapted to be rotated by the inflow of the combined air and fluid and a tube arranged in said casing below said wheel and above the fluid and air inlets forming a restricted passage for said fluid and air, substantially as described.

3. A carbureter for explosive-engines, comprising a casing, a disk or partition in the

lower portion of said casing provided with a fluid-inlet, a vertical pillar arranged on the upper side of said disk having vertical and transverse passages communicating with said fluid-inlet and a central perforation terminating in a valve-seat, a fan mixing-wheel rotatively mounted on said pillar and controlled by the action of the engine, a shaft fixed to said wheel and journaled in said perforation of the pillar, a valve at the extremity of said shaft operating in connection with said valve-seat to control the inflow of the fluid, an air-inlet below said fluid-inlet, a valve therefor, and a tube mounted in said casing and concentric with said pillar forming a restricted passage for the air and fluid leading to the said mixing-wheel, substantially as described.

4. A carbureter for explosive-engines, comprising a casing, a cover therefor provided with an adjustable screw leading within said casing, a disk or partition in the lower portion of said casing and provided with a fluid-inlet, a vertical pillar arranged on the upper

side of said disk, having vertical and transverse passages communicating with said fluid-inlet and a central perforation terminating in a valve-seat, a fan mixing-wheel rotatively mounted on said pillar and controlled by the action of the engine, a shaft fixed to said wheel and journaled in said perforation of the pillar, a valve at the extremity of said shaft operating in connection with said valve-seat to control the inflow of the fluid, an air-inlet below said fluid-inlet, a valve therefor, a tube mounted in said casing and surrounding said pillar, forming a restricted passage for the air and fluid leading to said mixing-wheel, and means at the bottom of said casing for regulating the inflow of air, substantially as described.

In witness whereof I have hereunto set my hand in the presence of two witnesses.

HENRI EDMOND CASGRAIN.
